UNITED STATES PATENT OFFICE

BURNHAM G. PRESTON, OF WEST MEDFORD, MASSACHUSETTS, ASSIGNOR TO NATIONAL COMPANY, INC., OF MALDEN, MASSACHUSETTS, A CORPORATION OF MASSACHUSETTS

ROLLER SKATE

Application filed November 27, 1926, Serial No. 151,079. Renewed January 23, 1930.

The present invention relates to roller skates, and more particularly to roller skates in which a single pair of enlarged wheels are disposed in the longitudinal median plane of the foot and at opposite ends thereof.

The object of the present invention is to provide a skate of this general type having relatively large wheels yet with a low centre of support, which is economical in manufacture, and which is of light, rigid and durable construction.

With these objects in view, the present invention consists in the skate hereinafter described and particularly defined in the claims.

In the accompanying drawings, Figure 1 is a side elevation of the preferred form of skate as applied to a shoe; Fig. 2 is a bottom plan view of the skate; and Fig. 3 is a section on line 3—3 of Fig. 2.

The illustrated embodiment of the invention comprises a skate having a frame or foot-supporting portion indicated generally at 4, on which are mounted wheels 6 at opposite ends thereof and in the longitudinal median plane of the foot. The frame is adapted for attachment to a shoe 8 of any desired form, by means of rivets.

The frame comprises an integral casting, preferably a die casting. It consists of a sole plate 10 for engagement with the sole of the shoe, and this plate is considerably narrower than the shoe to which it is to be attached in order that it will not strike upon the surface of the ground when the skate is inclined to one side or the other, either in straight-away speed skating or in making abrupt changes of direction. A longitudinal medial, vertical reinforcing rib 12 is formed on the frame for the purpose of lending strength to the entire structure, while permitting manufacture of the skate from material of light weight, such as is usually employed in the die casting art. At each end of the skate is a yoke 14 which extends upwardly and longitudinally from the frame, being formed as a continuation of the reinforcing rib 12. The wheels are journaled in the ends of the yokes and by the upward curvature of the yokes as illustrated in Fig. 1, the center of gravity

of the structure is maintained below the axis of rotation of the wheels, thus conducing to stability and facility of operation.

The wheels 6 it will be noted, are of sufficient size to pass over irregularities in the ground surface, without transmitting undue shocks to the foot of the wearer, and are preferably provided with rubber tires and ball bearings in order to render an excursion on the skates smooth and pleasurable, while requiring sufficient effort for their propulsion to afford an exhilarating pastime.

Having thus described the invention, what is claimed is:

1. A skate comprising an integral frame having a horizontal sole plate, a vertical reinforcing rib for the sole plate and integral therewith throughout the length of the plate, and yokes extending upwardly and longitudinally from the sole plate and rib on both ends of the frame and lying wholly above the lowermost point of the rib, and wheels journaled in the yokes.

2. A skate comprising a rigid and unyielding integral frame having a sole plate adapted for attachment to a shoe and of less width than that of the shoe to which it is to be attached, and yokes formed integrally with the sole plate and extending upwardly and outwardly from opposite ends of the sole plate, the plate at each end overlying and merging into the yokes and wheels journaled in the yokes.

3. A skate comprising an integral casting having a sole plate and a medial, vertical, reinforcing rib, the rib being extended longitudinally at opposite ends of the sole plate to form yokes, the yokes extending upwardly with their free ends located a substantial distance above the sole plate, and wheels journaled in the yokes.

4. A skate comprising a rigid integral casting having a sole plate, a vertical reinforcing rib below the sole plate, yokes formed integrally with the sole plate and the rib and extending outwardly and upwardly from opposite ends thereof, the sole plate at each end merging into the yokes adjacent the rib with the top surface of the plate coincident with the top surface of the yokes at the point

of merger, the yokes being of a width at least as great as that of the rib, and wheels journaled in the yokes, the center of gravity of the skate being below the axis of rotation of the wheels.

5. A roller skate having but two wheels arranged one in front of the other, a rigid foot-support located between said wheels and located in a plane below a plane passing through the centers of the said wheels, said foot-support being formed longitudinally to present an upper surface which is lower adjacent to the front wheel than it is adjacent to the rear wheel thereby to conform substantially with a foot of the wearer and yokes extending from the foot-support and attached to the wheels to support said foot-support between them.

6. A roller skate having a foot-supporting plate, a reinforcing rib below said foot-supporting plate, yokes extending upwardly from beneath the ends of the foot-supporting plate and having wheels journaled in their free ends, the centers of said wheels being located substantial distances above the plane of said foot-supporting plate.

In testimony whereof I hereunto sign my name to this specification.

BURNHAM G. PRESTON.
